US00D883752S

(12) **United States Design Patent** (10) Patent No.: **US D883,752 S**
(45) Date of Patent: **** May 12, 2020**

(54) **COOLER**

- (71) Applicant: **THE METAL WARE CORPORATION**, Two Rivers, WI (US)
(72) Inventors: **Richard Carey**, Manitowoc, WI (US); **Ross Niemi**, Two Rivers, WI (US)
(73) Assignee: **THE METAL WARE CORPORATION**, Two Rivers, WI (US)
(**) Term: **15 Years**
(21) Appl. No.: **29/670,188**
(22) Filed: **Nov. 14, 2018**

(57) **CLAIM**

The ornamental design for a cooler, as shown and described.

DESCRIPTION

FIG. 1 is a top perspective view of an embodiment of a cooler;

FIG. 2 is a front side view of the cooler of FIG. 1;
FIG. 3 is a back side view of the cooler of FIG. 1;
FIG. 4 is a right side view of the cooler of FIG. 1;
FIG. 5 is a left side view of the cooler of FIG. 1;
FIG. 6 is a top side view of the cooler of FIG. 1;
FIG. 7 is a bottom side view of the cooler of FIG. 1;
FIG. 8 is a top perspective view of the cooler of FIG. 1 with latches in a released position;
FIG. 9 is a front side view of the cooler of FIG. 1 without latches;

FIG. 10 is a top perspective view of a further embodiment of a cooler;

FIG. 11 is a front side view of the cooler of FIG. 10;
FIG. 12 is a back side view of the cooler of FIG. 10;
FIG. 13 is a right side view of the cooler of FIG. 10;
FIG. 14 is a left side view of the cooler of FIG. 10;
FIG. 15 is a top side view of the cooler of FIG. 10;
FIG. 16 is a bottom side view of the cooler of FIG. 10;
FIG. 17 is a top perspective view of the cooler of FIG. 10 with latches in a released position; and,
FIG. 18 is a front side view of the cooler of FIG. 10 without latches.

The broken lines in the drawings, if any, illustrate portions in the article that form no part of the claim.

1 Claim, 18 Drawing Sheets
